[57] ABSTRACT

An interlocking motor operated door and derailing device has a building protecting derailing apparatus that cannot be rendered ineffective while the door is closed. An electrical circuit operates through a solenoid opened lock to permit the derailing device to be rendered inoperative only when the door is fully opened and when a manually controlled switch is closed. A combination light and sound warning system is activated when the derailing device is rendered ineffective and train traffic lights are automatically operated to indicate that the door is open and the derailing device rendered ineffective.

Fig. 5

DERAILING DEVICE WITH SAFETY LOCK

This invention relates to railcar derailing devices and more particularly to an interlocking control for such devices.

Where rail-side tracks lead through openings into buildings wherein rail cars are loaded or unloaded, it is often necessary to provide closure doors for the openings to prevent access by weather as well as persons to the building. Where relatively long trains are operated and where the train locomotive engineer may be some distance away from the building entrance, it is desirable to provide a car derailing device to prevent a rail car from hitting a closed or partially closed door.

In order to insure that the derailing device is not accidentally moved to an inoperative position when the door is closed and that the door is not closed while the derailer is inactive, it is desirable that an interlocking control between the door, its operating means, and the derailing means be provided to insure proper operation.

It is therefore an object of this invention to provide a rail car derailing apparatus interconnected with a building door operator to protect the door.

It is further an object to provide such an apparatus whose protection function cannot accidentally or otherwise be eliminated.

These and other objects and advantages will be readily apparent from the following description and accompanying drawings in which:

FIG. 1 is a view of the invention in place on a track leading into a building;

FIG. 2 is a plan view of the derailing operating apparatus;

FIG. 3 is a sectional view taken on the line 3—3 of FIG. 4;

FIG. 4 is a further sectional view taken on the line 4—4 of FIG. 3;

FIG. 5 is a schematic diagram of the electrical control system for the invention; and

FIG. 6 schematically shows a dual track control for a single entrance door.

Referring now to FIG. 1 which shows a typical rail siding comprising rails 1 and 3 leading into a building 5 having a power operated door 7. Located adjacent to the rail 3 is the derailing apparatus which includes a wheel raising and derailing block 9 that is moved between an operative derailing position shown in FIG. 1 to a non-operative position inward of the rail 3. The derailing block 9 is connected to and is moved by link 11 pivotally attached to a lever 13 pivoted about the axis of pin 15 on a bracket 16 fastened on a tie member. An operating link 17 extends into a gear box 19 and is connected to be oscillated back and forth by an arm secured to a bevel gear 20, on a shaft 21 on which is mounted an indicator lamp 23. The bevel gear 20 is rotated by a right angle bevel gear 25 attached to a shaft 27 extending out from the gear box 19. The shaft 27 is adapted to be rotated through a 180° movement by an operating handle 29.

It will be seen that movement from the full line position shown in FIG. 2 to the broken line position in FIG. 2 will cause the gears 25 and 20 to be rotated with bevel gear 20 rotating 90° to rotate the indicator lamp 23 90°. The operating link 17 is also moved to the left and thus moves the derailing block 9 away from its operative position over the rail 3.

The operating handle 29 is normally held in its derailing position by a latch mechanism generally indicated 31. The latch mechanism includes a pivoted cam 33 having a locking portion 35 that acts to prevent the operating handle 29 from being raised. The pivoted cam 33 is suspended between mounting brackets 37. The mounting brackets 37 and pivoted cam 33 have apertures through which a locking pin 39 is urged by spring 41 into position to lock the pivoted cam 33 in its locking position shown in FIG. 3. The locking pin 39 can be retracted by energization of solenoid 43.

FIG. 5 illustrates the electrical control for the door, the interlock and various warning and indicator means. The control shown is usable with a dual track system

15 such as illustrated in FIG. 6 wherein a pair of tracks lead to a single entrance door in a building. The control includes a power supply having a step-down transformer 51 with one output winding supplying a pair of lines 53 and 55 and a second output winding supplying 20 a low voltage that is rectified by diode bridge 57 to supply low voltage lamps 59 located in the rotatable signal indicator lamps 23 which indicate the go or no go condition of the derailing apparatus located at B or C.

The building door is operated by a pair of motor relays MO and MC which operate a motor to open and close the door respectively. The relay MO is actuated by closing switch 61. Limit switches LS1 and LS2 are normally closed with LS2 opened by the door reaching its fully opened position to open the relay and stop the 30 motor. Normally closed contacts B1 on relay B and contacts C1 on relay C remain closed at this time. The door is closed by closing switch 63 to energize relay MC to operate the door motor to lower the door. Limit switch LS3 opens when the door reaches its fully closed 35 position.

When the limit switch LS4 is closed by the door reaching its open position, current is available to an interlock switch 65 which when activated actuates relay A which has a holding contact A1. Pilot lights 67 are energized to indicate that power is available to the derail control circuit by normally opened contacts A2 being closed when relay A is actuated. Solenoid 43 acts to pull its locking pin 39 (FIG. 4) against spring 41 to release the pivoted cam 33 on derail unit B for movement, while solenoid 71 operates in a similar way in derail unit C.

Relay A, in addition to the holding contacts A1 and the unlocking contacts A2, has normally closed contacts A3 and A5 acting to light red traffic or warning lights 79 and 80 warning that the derail unit is operative. Contacts A4 and A6 are normally open and are closed to permit energization of amber traffic lights 81 and 82.

With the locking pin 39 in position releasing pivoted cam 33, the same can be rotated away from the position shown in FIG. 3 to free derail operating handle for operation. The derail operating handle 29 of unit B and corresponding handle in unit C have mercury switches 75 and 77 attached thereto. When the operating handle 29 is in derail operation position shown in FIG. 2, the switch contacts are open. When the operating handle 29 is moved to non-derail position moving derailing block 9 away from the rail, the mercury switch 75 closes to energize a relay B having normally closed contacts B1 and B3 and normally open contacts B2 and B4. A relay C for derail unit C is similarly energized by closing of the mercury switch 77.

When relay B is energized, the contacts B1 open to prevent any further operation of the door motors which B3 opens to turn off the red traffic light 79 and contacts B4 close to light amber traffic light 81. This would indicate to the train crew that the derail unit is inoperative and that it is safe to move cars into the building. At the same time contacts B2 are closed to energize a motor flasher unit having contacts MF1 which energize flashing warning lights 83 and 85 to warn that a car may be entering the building. A sound alarm 87 is also operated by contacts MF2.

Overload contacts 89 and 91 act to open the door motor circuit if the door engages an obstacle either in raising or closing.

While the operation of the system can be followed from the above description, a brief summary of the operation is as follows. With the building door closed and the derailing unit operative as shown in FIGS. 1, 2 and 3, the closing switch 61 is manually closed to operate the door opening relay MO which energizes holding contacts MO1 and the door opens until limit switch LS2 opens to stop the motor. Limit switch LS4 closes to activate the interlock circuit. Interlock switch 65 is then manually operated to energize relay A and pilot lights 67 are lit. Contact A1 closes to hold the circuit and A2 closes to energize the unlocking solenoids 43 and 71. The locking pin 39 is retracted. Pivoted cam 33 is manually moved away from operating handle 29 which is then swung to move the derailing block away from the rail and turn the indicator lamp 23.

When operating handle 29 is operated, the mercury switch 75 closes to actuate relay B. Contacts B1 open to prevent further operation of the door, B2 closes to operate the warning lamps and alarm. B3 opens to turn off the red traffic light and B4 closes to turn on the amber light. The railcars can then be moved into the building. The parallel derailing system C would be operated in the same manner with relay C energized by moving the handle for derail unit C and mercury switch 77 energizing the relay C to set the alarm and traffic lights 80 and 82.

To reverse the operation after the railcar or the train is free of the entrance area, the operating handle 29 is again moved to move the derail block into operative position. Mercury switch 75 opens de-energizing relay B. Contacts B1 close to again energize the door operating circuit. The motor flasher MF is de-energized by contact B2 opening, amber traffic light 81 is turned off by contacts B4 opening and red traffic light 79 turned on by contact B3 closing. The latch or pivoted cam 33 is then moved to its locking position over the operating handle 29 and the door closing switch 63 is closed to activate the door motor closing relay MC. When the door reaches its closed position the limit switch LS3 opens to stop the motor.

When the door begins to close, the limit switch LS4 opens to deactivate relay A. Contacts A2 then open and the solenoid 43 is cut off allowing spring 41 to insert the locking pin 39 into the pivoted cam 33 to lock the same in place until the door is fully opened again.

It will be apparent that changes and modifications may be made to the apparatus and electrical circuit without departing from the spirit of the invention which is limited only by the following claims. For example, three or more derailing devices could be interconnected with the door control. Likewise, several motor

controlled doors could be interconnected with one or more derailing devices.

I claim:

1. A derailing apparatus for protecting a building and associated railcar door, said apparatus including door operating means, railcar derailing means having an operative and inoperative position and means operatively interconnecting said door operating means and said derailing means and wherein said door operating means comprises an electric motor, control means for said motor including normally closed relay contacts in series with said motor, actuating means for moving said derailing means from its operative position and switch means responsive to movement of said actuating means

10 to operate said relay to cause said contacts to open and thus prevent said motor from operating said door whenever said derailing means is not in an operative position.

2. A derailing apparatus for protecting a building and associated railcar door, said apparatus including door operating means, railcar derailing means having an operative and inoperative position and means operatively interconnecting said door operating means and said derailing means including locking means to positively 20 lock the derailing means in its operative position and means associated with said door for deactuating said locking means responsive to said door being in its open position.

3. The derailing apparatus of claim 2 wherein said derailing means comprises a derailing block movable between operative and inoperative positions by a manually operated linkage including a two position operating handle, mercury switch means on said handle adapted to energize a control circuit that effectively prevents said door operating means from being actuated.

4. A derailing apparatus for protecting a building and associated railcar door, said apparatus including door operating means, railcar derailing means having an operative and inoperative position and means operatively interconnecting said door operating means and said derailing means and wherein said derailing means is moved between its operative and inoperative position by an actuating device, controllable lock means for said actuating device normally locking the same in an operative derailing position and release means for causing said lock means to release said actuating means, said last mentioned release means operable only when said door is in its open position.

5. The derailing apparatus of claim 4 wherein the door is opened and closed by electric motor means, a motor control circuit for said motor means including a first switch for operating said motor means to cause door to open and a second switch to cause said door to close, an unlocking control circuit including a relay activated by the door being in its open position and by a manual switch, said relay having a first pair of normally closed contacts that are opened when the relay is actuated and which open the motor control circuit preventing operation of the door actuating means.

6. The derailing apparatus of claim 5 wherein said relay has a second pair of normally open contacts which are closed when the relay is opened and which cause activation of a warning device to indicate said lock means is inoperative to prevent said derailing means from being moved to its inoperative position.

7. The derailing apparatus of claim 6 wherein said relay has a third set of normally closed contacts opera-

tive to energize a stop warning light and which are opened by actuation of said relay and a fourth set of normally open contacts operative to energize a go light and which are closed by actuation of said relay.

8. A railcar derailing apparatus for derailing a railcar prior to collision with a movable device that is movable between a blocking and an unblocking position, and a control for the apparatus, said apparatus including a derailing device having an operative and an inoperative

position, manually actuated linkage for moving said device between its blocking and unblocking positions, a releasable latch for holding said linkage in derailing operative position and lock means normally preventing the latch from being released, electrical means for deactivating said lock means, electrical switch means for preventing actuation of said electrical means unless said movable device is in its unblocking position.
